The ornamental design for a chess board in packaging of protective case for electronic device, as shown and described.

DESCRIPTION

FIG. 1 is a perspective view of a chess board in packaging of protective case for electronic device showing our new design; FIG. 2 is a front elevational view thereof; FIG. 3 is a rear elevational view thereof; FIG. 4 is a left side elevational view thereof; FIG. 5 is a right side elevational view thereof; FIG. 6 is a top view thereof; FIG. 7 is a bottom view thereof. FIG. 8 is a perspective showing the chess board in an alternate configuration of use; and, FIG. 9 is a perspective view showing the chess board packaged with a protective case. The broken lines shown in the drawings depict environmental features that form no part of the claimed design.
